UNITED STATES PATENT OFFICE.

GEORGE S. COVELL, OF LYNN, MASSACHUSETTS, ASSIGNOR TO UNITED SHOE MACHINERY COMPANY, OF PATERSON, NEW JERSEY, A CORPORATION OF NEW JERSEY.

ROTARY SHOE-BEATING MACHINE.

1,003,434.

Specification of Letters Patent. Patented Sept. 19, 1911.

Application filed January 3, 1911. Serial No. 800,558.

To all whom it may concern:

Be it known that I, GEORGE S. COVELL, a citizen of the United States, residing at Lynn, in the county of Essex and State of Massachusetts, have invented certain Improvements in Rotary Shoe-Beating Machines, of which the following description, in connection with the accompanying drawings, is a specification, like reference characters on the drawings indicating like parts in the several figures.

This invention relates to machines for use in the manufacture of boots and shoes and particularly to shoe-shaping machines and is embodied in a machine of the type shown in printed British Patent No. 16,589/08.

The invention comprises certain improvements upon the machine shown in that patent designed to perfect the operation of that machine on certain classes of work and to render that machine more durable. This type of machine comprises a rotary beater that includes a hub having annular flanges between which flanges extend rods upon each of which is mounted a plurality of rings the interior diameter of which is substantially greater than the diameter of the rod. This arrangement provides that the rings shall stand out radially from the hub by centrifugal action while the beater is rotating and that the rings may yield inwardly when they strike the work and may swing backwardly on the rods as they glide over the work in rubbing contact therewith. It has been found in practice that the operation of this machine is wonderfully effective in such work, as, for example, in beating down the overlasted marginal portion of an upper because of the great number of blows struck on the work per minute by the somewhat light rings. The machine used commercially strikes about forty-eight hundred blows per minute. This great effectiveness of the beater has led to the extension of its field of operation and it is now used for beating out soles of turn shoes and for beating the upper around the sides of shoes for shaping the upper to the last. In this operation upon the shoe upper and upon the damp tempered soles of turn shoes it has been found that the rings of the machine shown in the patent crease the soft stock and leave a perceptible line be-

tween each laterally adjacent series of rings, this line being slightly raised. It is to overcome this difficulty that an important feature of this invention has been devised. In accordance with this feature of the invention the rings carried by one rod are arranged in staggered relation to the rings carried by the rods on either side whereby the rings on each rod obliterate the lines and beat down the ridges which may be left between the adjacent rings on the rod that precedes it in the rotation of the beater. In the construction shown this result is obtained by employing on each alternate rod end rings which are one and one-half times the width of the other rings. In the practical use of this machine through an extended period of time it developed that the turning action of the rings upon their rods as the rings strike the work and swing backwardly in gliding over it turned the rods in the flanges of the hub and that the severe outward pull of the rings caused by centrifugal force tended to wear the end portions of the rods that are contained in the flanges. Experiments in the choice of suitable materials reduced this action somewhat but the wear was sufficient to weaken the rods in the course of time and render possible an accident resulting from a rod giving way while the beater was in use and throwing the rings into the room and possibly against the operator. To overcome this wearing of the rods and remove liability of such an accident I have provided novel means for preventing the rotation in this beater of the rods upon which the rings swing. This is accomplished by cutting into the outer face of one or both of the flanges of the hub an annular groove extending in the same circle as the holes in the flange into which the rods project. I have also formed in the end of each rod a recess and in assembling the beater the recess in the rods is arranged in alignment with the groove in the hub flange and a wire or hoop is laid in this continuous groove and constitutes a key which prevents turning movement of the rods in the flanges. The key is confined in place by an annular plate that is attached to the outer face of the flange.

The several features of the invention in-

cluding certain details of construction and combination of parts will appear in the following description of the machine.

Figure 1 is a front elevation of the machine; Fig. 2 is a side elevation, partly in section; Fig. 3 is an inverted plan view showing the action of the beater upon a shoe sole.

The frame of the machine supports a shaft 2 upon which is mounted a hub having end flanges 4 in which are supported the end portions of rods 5 that carry rings 6. The internal diameter of the rings is substantially larger than the rods so that the rings are held outward by centrifugal force while the beater is rotating. This arrangement allows the rings to strike the work by impact with a gliding blow and after having contacted with the work to swing backwardly around the rod as they glide over the work. This action will be clearly understood from Fig. 2 in which a ring is shown as having struck the work and as being turned backwardly about the rod as it continues its movement over the work. The rings are adapted to move relatively to one another as they strike the work in order to adapt themselves, that is, to present an acting face conforming to the contour of the work. In practice there is necessarily a little looseness or play between the rings and their annular edges are slightly rounded as at 7 to avoid marking the stock. Upon soft stock such as the tempered soles of turn shoes and some upper materials this formation of the rings tends to leave lines or ridges. As herein shown, the end rings 61 on each alternate rod are one and one-half times the width of the other rings thereby producing a staggered relation of the rings on adjacent rods whereby the rings on one rod beat out and obliterate the lines or ridges left by the rings on the preceding rod.

The rods 5 are shown as confined against endwise movement in holes or sockets in the right hand flange or disk 4. At their left hand ends the rods project through an annular series of holes in the flange and are each provided with a transverse opening or slot. The flange is formed with an annular groove 10 passing through the rod openings. In assembling the beater the rods are arranged with their openings in alinement with the openings in the groove and a wire or hoop 12 is placed in the groove in engagement with a wall or walls formed by the openings in the rods. The wire 12 thus constitutes a continuous key, extending around the beater and preventing each of the rods from turning in its bearing in the flange. For confining the wire in place and preventing any endwise movement of the rods toward the left a cover plate 14 is attached by screws to the outer end face of the left hand flange. The cover plate pref-

erably has holes located over the ends of the rods but of smaller diameter than the rods and through which the ends of the rods and the wire 12 may be seen to determine at any time if the wire has been sheared off and any rod has thus been freed to turn in its bearings.

Obviously, the construction which is described for the left hand end of the beater may also be employed at the right hand end but this has not been found to be necessary.

The described construction has proven sufficient to prevent the turning of the rods and the wear of the rod ends which would result from such turning and would in time weaken the rods so that they might give way to the powerful centrifugal force which they are called upon to withstand in the rotation of the beater at the high speed at which it is driven in the commercial machines.

Having explained the nature of this invention and described a preferred construction embodying the same, I claim as new and desire to secure by Letters Patent of the United States:

1. In a machine of the class described a rotary beater comprising a carrier and beating members arranged about the periphery of the carrier, each member consisting of a plurality of rings mounted for swinging movement about their connection with the carrier, the rings of one member being arranged in staggered relation to the rings of another member, for the purpose described.

2. In a machine of the class described, the combination with a rotary shaft, a pair of disks carried by the shaft, and pivot rods supported by said disks; of beating members mounted on said rods between the disks, said beating members comprising rings encircling the rods, the rings on one rod being arranged in staggered relation to the rings on the adjacent rods and having openings larger than the rods whereby they are held outwardly by centrifugal force during the rotation of the shaft and may yield inwardly against that force under pressure of the work against them.

3. In a machine of the class described a rotary beater comprising a carrier and beating members arranged about the periphery of the carrier, each member consisting of a plurality of rings mounted for swinging movement about their connection with the carrier, the series of rings constituting each alternate member including end rings 61 which are one and one-half times the width of the rings of the other beating member, as and for the purpose described.

4. In a machine of the class described, a rotary beater comprising a carrier having end flanges, a series of rods having their ends supported in said flanges, rings loosely

5 mounted to turn on the rods and pressed outwardly by centrifugal force while the carrier is in motion, and means common to a plurality of rods for restraining the rods from turning in the carrier flanges.

10 5. In a machine of the class described the combination of a rotary hub, a pair of disks carried by the hub, pivot rods supported at their ends by said disks, and means for restraining said rods from turning in said disks, of beating members mounted on said rods between the disks, said beating members comprising rings encircling the rods and having openings larger than the rods 15 whereby they are held outwardly by centrifugal force during the rotation of the hub and may yield inwardly and swing backwardly against that force under pressure of the work against them.

20 6. In a machine of the class described, the combination with a rotary hub, a pair of disks carried by the hub, an annular series of holes in the disks, pivot rods mounted in said holes, beating elements 25 mounted on said rods between the disks and tending to turn the rods as said elements engage and pass over the work during the beating operation, and means for restraining the pivot rods from turning in the holes 30 in the disks.

35 7. In a machine of the class described, the combination with a rotary hub, a pair of disks carried by the hub, an annular series of holes in the disks, pivot rods mounted in said holes, beating elements 40 mounted on said rods between the disks

45 and tending to turn the rods as said elements engage and pass over the work during the beating operation, one of said disks and the end portions of the rods mounted therein being formed with a continuous annular groove, and an annular key confined in said groove in the disk and rod ends for preventing turning movement of the rods.

50 8. A rotary beater having, in combination, the end disks 4, rods 5, and rings 6, said rods having their ends supported in the disks and having transverse openings through the ends that are carried by one of the disks, and a wire extending around the beater and confined in the openings in the 55 ends of the rods.

55 9. A rotary beater having, in combination, the end disks 4, rods 5, and rings 6, said rods each having an end supported in a socket in one of the disks and having transverse openings in the ends that are carried by the other disk, said second disk having an annular groove 10 extending through said openings, an annular key 12 60 extending through said groove and said openings, and an annular plate 14 attached to the outer face of said second disk for confining the wire and the rods.

65 In testimony whereof I have signed my name to this specification in the presence of two subscribing witnesses.

GEORGE S. COVELL.
